[57] CLAIM

The ornamental design for a combined bottle and cap, as shown and described.

DESCRIPTION

FIG. 1 is a perspective view of a combined bottle and cap, showing our new design;

FIG. 2 is a top plan view thereof;

FIG. 3 is a left side elevational view thereof, the right side being identical;

FIG. 4 is a front elevational view thereof, the rear elevational view being identical; and

FIG. 5 is a bottom plan view thereof;

FIG. 1 is shown on a larger scale than FIGS. 2 through 5.
